UNITED STATES PATENT OFFICE

FERDINAND JEHLE, OF CLEVELAND, OHIO, ASSIGNOR TO THE WHITE MOTOR COMPANY, OF CLEVELAND, OHIO, A CORPORATION OF OHIO

THROTTLE MECHANISM FOR INTERNAL-COMBUSTION ENGINES

Application filed February 27, 1929. Serial No. 343,083.

This invention relates to internal combustion engines and more particularly to throttle mechanism therefor.

It is an object of this invention to provide in connection with a plurality of engine intake conduits a mechanism which will maintain equal fluidic pressures within the separate conduits.

It is a further object of this invention to provide in connection with a plurality of engine intake conduits a simple and efficient mechanism which will operate and control a throttle valve in one of the conduits in response to a second throttle valve located in another of the conduits.

Other objects will hereinafter appear.

The invention itself will be more readily understood from the description of one practical embodiment, illustrated in the accompanying drawings in which:

Figure 1 is a front end elevation of a pair of internal combustion engines, certain parts of which are broken away in the interest of clarity, and

Figure 2 is a longitudinal sectional view of a portion of the throttle control mechanism shown in Figure 1.

Referring to the drawings, the numerals 10 and 11 indicate a pair of internal combustion engines which are connected by gearing (not shown) so as to have equal rates of crankshaft rotation. These engines, with the exception of certain dissimilarities to be hereinafter described, are allochiral copies of one another. As clearly illustrated, they comprise counterpart intake pipes 12 and 13, respectively, which communicate with separate carburetors 14 and 15 of identical construction.

Pivottally mounted within the intake pipe 12, there is a throttle valve 16 operatively connected by a linkage 17 with the sliding sleeve 18 of a governor 19.

The linkage 17 comprises a link 20 fulcrumed on the casing 21 of the governor 19, and a link 22 connecting the outer end of the link 20 with an operating arm 23 secured to the valve pivot pin 24.

The governor 19 comprises a shaft 25 rotatably mounted within the casing 21. Se-

cured to the lower extruding portion of the shaft 25, there is a gear-wheel 26 which meshes with a gear-wheel 27 mounted on the camshaft 28 of the engine. Rigidly attached to the shaft 25 and having a bearing on a seat 29 formed on the lower wall of the casing, there is a member 30 which supports a pair of pivotally mounted governor weights 31. The sleeve 18 is slidably mounted upon the shaft 25 above the member 30, and is pressed into engagement with the inwardly extending arms 32 of the governor weights 31 by means of a spring 33.

As will be readily apparent to those skilled in the art, the governor 19 by means of the linkage 17 will limit the speed of the engine 10 to a maximum rate which is dependent upon the strength of the spring 33.

As clearly shown in the drawing, the carburetors 14 and 15 are formed with tubular portions 34 which join with intake pipes 12 and 13, and which for all practical purposes may be considered as extension of the intake pipes. Pivottally mounted in the tubular extension 34 of the carburetor 14, there is a manually controlled throttle valve 35 which may be connected to a control lever (not shown) by means of a link 36 attached to the valve operating arm 37.

Affixed to the intake pipe 13, there is an outwardly extending cylinder 38 of uniform internal diameter. This cylinder communicates with the intake pipes 12 and 13 by means of separate conduits 39 and 40 which lead from its opposite ends. Mounted within the cylinder 38 is a piston 41 which, as will be readily apparent, is subjected at one end to the pressure existing in the intake pipe 12, and at its opposite end to the pressure existing in the intake pipe 13.

Mounted within the tubular portion 34 of the carburetor 15, there is a pivotally mounted throttle valve 42 operatively connected to the piston 41 by means of a linkage 43.

The linkage 43 comprises a link 44 fulcrumed on an arm 45 secured to intake pipe 13, and a link 46 connecting the lower end of the link 44 with the valve operating arm 47.

Assuming the engines in Figure 1 to be running, and equal pressures to have been established within their respective intake pipes 12 and 13, it will be apparent that the production of unequal pressures within pipes 12 and 13 by a separate or combined movement of the valves 16 and 35 will cause the piston 41 to move the valve 42 to a position wherein it will produce a pressure within the pipe 13 equal to the pressure within the pipe 12.

Since the valve 42 is actuated by the piston 41 in response to unequal pressures initiated within the pipes 12 and 13 by separate or combined movements of the valves 16 and 35, it can properly be said that the valve 42 is operated and controlled in response to the valves 16 and 35.

It will be apparent that, if the motors 10 and 11 embodying the present invention, were substituted for the motors of a vehicle of type disclosed in United States Patent Number 972,455, the motors would be connected by a connection consisting of the vehicular driving mechanism and ground, which for the purpose of the present invention would constitute an equivalent of the gear-connection described in forepart of the specification.

It will be further apparent, that the throttle mechanism herein illustrated and described is not limited in its application to the intake pipes of separate engines, but may be used in conjunction with intake pipes of the same engine.

It will further be apparent that various other changes and modifications may be resorted to without departing from the spirit of this invention, and it will be understood that the invention is not limited to the precise construction and arrangement shown and described.

I claim as my invention:

The combination with a pair of internal combustion engine fuel supply systems, of a movable member subjected on one side to the fluidic pressure existing in one of said systems and on its opposite side to the fluidic pressure existing in the other of said systems, a throttle valve for one of said system operatively connected to said member, and a manually controlled throttle valve and a governor-controlled valve for the other of said systems.

In testimony whereof I hereunto affix my signature this seventh day of February, 1929.

FERDINAND JEHLE.
